UNITED STATES PATENT OFFICE.

OSCAR PATRIC OSTERGREN, OF NEW YORK, N. Y.

ELECTRIC CONDUCTOR.

SPECIFICATION forming part of Letters Patent No. 650,987, dated June 5, 1900.

Application filed June 27, 1899. Serial No. 722,013. (No model.)

To all whom it may concern:

Be it known that I, OSCAR PATRIC OSTERGREN, a citizen of the Kingdom of Sweden, and a resident of New York, (Brooklyn,) county of Kings, State of New York, have invented certain new and useful Improvements in Electric Conductors, of which the following is a specification.

My invention relates to improvements in electric conductors; and it consists in providing a conductor which will present but slight resistance to the passage of the currents, and thus prevent or reduce to a minimum leakage of the electric fluid, which has here-
15 tofore invariably resulted.

My device is particularly applicable where the conductor is to be placed underground and where the conductivity of the surrounding earth in spite of the most perfect insulation results in a great loss of the electric fluid.

It is well known that a conductor for electricity is far more efficient at a low temperature than at a high temperature, and it is my purpose to provide means whereby the conductor may be reduced to and maintained at an extremely-low temperature. To this end I bring the conductor in contact with or in close proximity to a current of liquid air, and thus reduce the temperature of the conductor
25 to that or substantially to that of the liquefied air.

I will now proceed to describe my invention with reference to the accompanying drawings and will then point out the novel features in
35 claims.

Figure 1 is a diagrammatical view of a liquid-air system which may be employed in connection with my improved electric conductor. Fig. 2 is a transverse sectional view, on an enlarged scale, taken on the line 2 2 of Fig. 1. Fig. 3 is a similar section on the line 3 3 of Fig. 1. Fig. 4 is a similar section on the line 4 4 of Fig. 1. Fig. 5 is a transverse section taken on a similar plane to Fig. 2, but
45 of a slightly-modified form of construction. Figs. 6 and 7 are views similar to Fig. 2, but illustrating slight modifications thereof.

Similar reference characters designate corresponding parts throughout the several
50 views.

Reference character 8 designates a hollow tube of indefinite length. This hollow tube I preferably make of pure copper, in which case I use the tube itself as a conductor of

electricity as well as a conduit for liquid air. 55 I do not confine myself to such material, however, or to such combined use, as I may make the tube of some electrical non-conducting material, such as porcelain or glass, and provide independent conductors for the electricity, as in Figs. 6 and 7. In Fig. 6 I have shown these conductors in the form of wires 25, arranged on the outside of the tube 8, and in Fig. 7 I have shown a single wire on the side of said tube immersed in the liquid air. 65

Referring now more particularly to Figs. 1 and 2, reference character 9 designates a pump, 10 a cooler, and 11 a condenser. The air to be liquefied is taken in and initially compressed by the pump 9. It is then cooled in 70 the cooler 10 and liquefied in the condenser 11. From the condenser 11 it is forced into the tube 8 through the connection 12. 13 designates a dome or pressure-chamber communicating with said tube. The products of 75 evaporation rising in said dome or pressure-chamber maintain a constant pressure, tending to drive the liquid air through the tube 8.

Reference character 14 designates a dynamo electrically connected with the conductor and arranged to supply the electricity which is to be transmitted thereby.

My preferred arrangement for insulating the tube 8, either electrically or from the influences of external heat, is as follows: I surround tube 8 with the porous casing 17 of suitable material and construction, leaving a space 18 between said casing and said tube 8. This space may be maintained by the use of suitable spacing-pieces, as designated by reference character 26 in the drawings. Detail description of these spacing-pieces as to their construction and arrangement is unnecessary, as forming no part of this invention. I arrange at intervals at the top of the tube 8 95 a blow-off valve 19, set at a predetermined pressure. The said blow-off valve communicates on its discharge side with the space 18 between the exterior of the tube 8 and the interior of the casing. I provide also an outer 100 sheathing 20, preferably metallic, said outer sheathing inclosing a space 22, surrounding the porous casing, having orifices 21. When the products of evaporation from the liquid air in tube 8 reach a pressure above that at 105 which the blow-off valve is set, they will escape through said valve into the space 18 surrounding said tube and will gradually force

their way through the porous casing into the chamber 22, and from thence escape through the orifices 21, repelling the warm air on the exterior of the casing, and thus effectively insulating the inner tube 8 and reducing the evaporation in said tube. The porous casing and outer sheathing, together with the chambers inclosed thereby, run the full length of the inner tube, and the blow-off valves are arranged within the inner tube 8 at proper intervals along its length.

The porous casing may be constructed of any suitable material. I have here shown it as consisting of two sheathings of perforated metal or wire-mesh, inclosing between them granulated corn-pith, wood fiber, or the like, or the casing may be made of porous carbon, compressed cork, or any other like material.

If desired, I may replace the liquid air lost through evaporation by means of relays, as shown in Fig. 1, in which case I can conveniently use a portion of the electricity to drive a motor 15 for actuating the pump 9^a. The operation is the same as that already described with reference to pump 9. The air is taken in and compressed by the pump 9^a and is cooled in the cooler 10^a and liquefied in the condenser 11^a, and from thence forced into the tube 8 through the connection 12^a, at which point a dome 13, similar to that shown in Fig. 4, may be inserted to maintain pressure to drive the liquid air through the tube in a manner already described. I have shown a second dynamo or generator 16 as connecting electrically with the conductor, such generator being for the purpose of supplementing the dynamo or generator 14 in a case where the said conductor is of great length. As the length of the said conductor is increased, so further generators may be added to an indefinite number, as may also additional apparatus for the further supply of liquefied air. If desired, I may utilize the liquefied air and said products of evaporation by employing suitable valves and connections, as shown in Fig. 5, the connection 23 leading to a motor, refrigerating apparatus, or the like. In this case I omit the orifices 21 at or about the place where the valves and connections are placed for drawing off said products of evaporation, thus making the outer sheathing a closed casing, and I preferably employ a second blow-off valve 24 to be used as a safety-valve to prevent an unusual amount of pressure accumulating in the said connection 23.

What I claim is—

1. The combination with a dynamo or electric generator, and an air-liquefying apparatus, of a conduit adapted to receive and convey liquefied air from the air-liquefying apparatus, the said conduit composed of electrically-conductive material, and electrically insulated from surrounding objects, and the said conduit electrically connected with the said electric generator and adapted to receive and convey electric currents therefrom.

2. The combination with a conduit for liquefied air or other liquefied gas, the said conduit composed of electrically-conductive material, of liquefying apparatus connected to said conduit and adapted to supply same with liquid air or other liquefied gas, an electric generator electrically connected to said conduit and adapted to transmit an electric current to said conduit, and an electric motor electrically connected to said conduit and adapted to receive its motive power therefrom and arranged in its movement to operate the liquefying apparatus.

3. The combination with a dynamo or generator and an electric conductor for conveying currents of electricity therefrom, the said electric conductor arranged to be in close proximity to, liquefied air or other liquefied gas, of liquefying apparatus adapted to supply liquefied air or other liquefied gas thereto and an electric motor connected to said electric conductor and adapted to receive its motive power therefrom and arranged in its movement to operate the liquefying apparatus.

4. The combination with a dynamo or electric generator, and an electric conductor for conducting currents of electricity therefrom, the said electric conductor arranged to be in close proximity to, liquefied air or other liquefied gas, of liquefying apparatus adapted to supply liquefied air or other liquefied gas thereto, at or near one end of the said conductor, supplementary air-liquefying apparatus, and an electric motor connected to said electric conductor and adapted to receive its motive power therefrom, and arranged in its movement to operate the supplementary liquefying apparatus.

5. The combination with a dynamo or electric generator, and an air-liquefying apparatus, of a conduit adapted to receive and convey liquefied air from the air-liquefying apparatus, the said conduit composed of electrically-conductive material, and electrically insulated from surrounding objects, and the said conduit electrically connected with the said electric generator and adapted to receive and convey electric currents therefrom, supplementary air-liquefying apparatus, and an electric motor electrically connected to said conduit and adapted to receive its motive power therefrom, and arranged in its movement to operate the supplementary liquefying apparatus.

6. The combination with the conduit for liquefied air, or other liquefied gas, of a source of supply for the liquefied air, and a dome, or air-chamber, between said source of supply and said conduit.

Signed by me at New York, N. Y., this 16th day of June, 1899.

OSCAR PATRIC OSTERGRENN.
